(57)

CLAIM

The ornamental design for a leadframe, as shown and described.

DESCRIPTION

FIG. 1 is a top perspective view of a leadframe showing our new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top perspective view of a leadframe showing a variation of our new design;

FIG. 8 is a top plan view thereof;

FIG. 9 is a front elevational view thereof;

FIG. 10 is a rear elevational view thereof;

FIG. 11 is a right side elevational view thereof; and,

FIG. 12 is a left side elevational view thereof.

The broken lines in the figures represent unclaimed subject matter and form no part of the claimed design.

The shade lines in the figures show contours and not surface ornamentation.

1 Claim, 12 Drawing Sheets(56)
